UNITED STATES PATENT OFFICE

BENJAMIN L. FRIEDMAN AND STEPHEN KOVAC, OF ROEBLING, NEW JERSEY

MOP HEAD AND WRINGER

Application filed June 11, 1928. Serial No. 284,618.

This invention relates to improvements in combined mop holders and wringers and has as its general object to provide a device of this class which will present advantages over similar devices now in use.

Another object of the invention is to provide in a mop, a novel construction of head for supporting and backing the mop cloth, the construction being such that the cloth will be held flat against the floor surface while the mop is in use in mopping the floor thus adapting the cloth to cover more surface than in the ordinary types of mops and thus expedite the mopping operation, the 10 mop head being capable, in another position of adjustment, to so hold one end of the mop cloth as to provide for the efficient operation of a means which is provided for twisting the cloth to wring the surplus water therefrom.

Another object of the invention is to provide novel means for connecting one end of the mop cloth with the head of the mop so that the mop cloth will be maintained in a spread out or flat condition during the period 25 of use of the mop, the said means being further so constructed and mounted as to provide for disconnection of this end of the mop cloth when it is desired to thoroughly clean the same or substitute a new cloth.

Another object of the invention is to provide a wringing means which will be extremely simple in construction and inexpensive to manufacture and in this connection the invention also has as its object to so 35 construct the wringing means that it will serve at all times as a support for the rear end of the mop cloth and therefore be capable of being instantly brought into use when it is desired to wring the cloth.

While the accompanying drawing and the description which is to follow, constitute a disclosure of the preferred embodiment of the invention, it will be understood that various changes may be made within the scope 45 of what is claimed.

In the accompanying drawing:

Figure 1 is a view in side elevation of the mop head and wringer embodying the invention;

Figure 2 is a top plan view thereof;

Figure 3 is a vertical longitudinal sectional view on the line 3—3 of Figure 2, the view illustrating the mop head in the position which it will occupy when the device is employed in mopping floors and in broken lines 55 in position when the wringer is being employed;

Figure 4 is a vertical transverse sectional view taken substantially on the line 4—4 of Figure 1 looking in the direction indicated 60 by the arrows;

Figure 5 is a perspective view of the mop head and wringer.

The mop head is indicated in general by the numeral 1 and the handle, to which the 65 head is connected by a means to be presently described, is indicated in general by the numeral 2. The mop head preferably comprises a sheet metal body 3 having the general marginal contour shown in the several figures of 70 the drawing, and, for a purpose to be presently explained, the head 3 is formed at its opposite sides and at its forward end with lateral extensions which are bent up or rolled for a portion of their length as indicated by 75 the numeral 4 and which have their upper portions bent or rolled upwardly and outwardly along curved lines as indicated by the numeral 5, these portions defining sockets 80 at the opposite sides of the plate 3 of the head at the forward corners thereof. The holding means for supporting the forward end of the mop cloth, which cloth is indicated by the numeral 7, is indicated in general by the numeral 8 and preferably is 85 formed from a single length of wire bent to provide spaced parallel side members 9 and a connecting front member 10, the wire, at the juncture of the forward ends of the side members 9 and the said front member 10 being 90 provided with outstanding bends 11. The rear ends of the side members 9 of the mop supporting member 8 are turned outwardly at right angles as indicated by the numeral 12 and these end portions are engaged in openings 13 formed in ears 14 which 95 are struck up from the plate 3 of the head. The member 8 will preferably be formed of resilient wire and, when the member is assembled with the head 1, the side members 100

9 will have interlocking engagement in the seats 6 provided by the members 4 of the head 1, at points inwardly of the bends 11, the member 8 being in this manner securely held in flat position upon the upper side of the plate 3. At this point it will be observed that the bends 11 project laterally beyond the respective side members 9 of the member 8 so that when the forward end of the mop 7 is properly engaged over the portion 10 of the member 8, the mop cloth at this end may expand to its full maximum width and therefore its portion which extends rearwardly beneath the head 1 will extend at its lateral margins beyond the corresponding margins of the plate comprising the head.

In order that, when found necessary, the end of the mop cloth which is connected with the portion 10 of the supporting member 8 may be disconnected from the said member, it is only necessary to spring the side members 9 of the said member inwardly until they disengage from the sockets 6 and at their ends 12 from the openings 13 in the ears 14 whereupon the member 8 may be bodily moved away from the plate 3 and turned to a substantially right angular position within the said end of the mop cloth and the engaged one of its side members 9 slid through the end of the cloth.

The connection provided between the mop handle 2 and the head 1 comprises a yoke 15 which is disposed to straddle the lower or forward end of the said handle 2 in the manner clearly shown in the drawing, the yoke being formed in its opposite sides with openings, and screws or other fastening elements 16 being fitted through these openings and into the said end of the handle 2 so as to secure the yoke in place upon the handle. The yoke 15 is provided at its lower or forward end with depending side portions 17, and a link 18 is disposed between these depending side portions and a pivot pin 19 is secured through the upper end of the link and through the said side portions. The link 18 is preferably of the formation shown in the drawing and comprises spaced side portions and a connecting portion extending therebetween, the link being preferably formed from a sheet metal blank folded to provide the said portions. The lower end of the link 18 is disposed between a pair of upstanding ears 20 which are struck up from the plate 3, and a pivot pin 21 is mounted at its ends in openings in these ears and extend through the said lower end of the link 18. Due to the peculiar formation of the link 18, a substantial pivotal connection is provided between the handle of the mop and the mop head.

From the portion 10 of the supporting member 8, the mop cloth 7 is led rearwardly beneath the plate 3 comprising the mop head and is connected with the wringing device 65 of the mop which device is indicated in gen-

eral by the numeral 22. The said wringing device is preferably formed of a single length of wire which is bent to provide an open oblong head 23 through which the rear end of the mop cloth may be extended, and a shank 70 portion 24 which is rotatably journaled in a bearing bushing 25 which is fitted through an opening 26 formed in the handle 2 and through the upper end of the yoke 15 and headed to be held in place. The head 23 is located at the lower end of the stem 24 and therefore beneath the handle 2, and the upper end of the stem is formed to provide a crank handle indicated by the numeral 27 having an upturned outer end provided with a hand knob 28 whereby rotary motion may be imparted to the stem 24 to cause rotation of the head 23 and a twisting of the mop cloth to wring the surplus water therefrom. When the wringing device is to be employed, the mop head 1 is swung downwardly from the full line position shown in Figure 3 of the drawing to the broken line position in which position it will extend downwardly beneath the forward end of the handle 2 and with its portion 18 resting in engagement against the downward side extensions 17 of the yoke 15, the engagement of the portion 18 of the head 1 against these portions of the yoke serving to limit the rearward movement of the head beyond the dotted line position shown in the said Figure 3 and thus permit of operation of the crank handle to effectually twist the mop cloth and wring the surplus water therefrom.

In order that the side members 9 of the mop cloth holder 8 may be conveniently engaged by the hands of the user when sprung inwardly to separate the holder from the head 1, the body 3 of the head 1 is preferably formed in its opposite longitudinal edges, between the upturned portions 4 and the pivot ears 14, with arcuate recesses indicated by the numeral 29, these recesses being sufficiently deep to extend inwardly beyond the side members 9 when these members are in their expanded or normal position.

Having thus described the invention, what we claim is:

A mop comprising a handle, a head formed from a blank sheet of metal comprising an elongated body, means for connecting said body to said mop handle, upwardly extending apertured ears bent from the side edges of said body, lateral extensions rolled for a portion of their length and having their upper portions bent upwardly and outwardly along curved lines for producing sockets at the forward corners of the body, said body provided with arcuate recesses along the side edges thereof of material depth intermediate said ears and said lateral extensions, and a mop holding means formed from a single strand of wire having a pair of substantially parallel arms spanning said arcuate recesses

and terminating in oppositely and outwardly extending ends adapted to extend through said apertured ears from the inside toward the outside thereof, said arms being adapted to swing under the inner faces of said lateral extensions for locking said mop holding means in engagement with said body, said recesses permitting the withdrawal of the outwardly extending ends from said apertured ears through the inward movement of said arms when gripped by the fingers of an operator.

In testimony whereof we affix our signatures.
